(57) **CLAIM**

The ornamental design for a tennis swing trainer with a bungee, as shown and described.

DESCRIPTION

FIG. 1 is a perspective view of the tennis swing trainer with a bungee showing our new design;

FIG. 2 is a front view thereof;

FIG. 3 is a rear view thereof;

FIG. 4 is a top view thereof;

FIG. 5 is a bottom view thereof;

FIG. 6 is a right end view thereof; and,

FIG. 7 is a left end view thereof.

The bungee element is shown broken away to indicate indeterminate length.
